TELEPHONE SYSTEM

John Wicks, Oak Park, Ill., assignor, by mesne assignments, to Associated Electric Laboratories, Inc., Chicago, Ill., a corporation of Delaware

Application August 17, 1931, Serial No. 557,566
Renewed November 17, 1932

21 Claims. (Cl. 179—16)

The present invention relates to telephone systems in general, but is concerned more particularly with telephone systems employing automatic switches to set up the telephone connections; and the main object is the production of a new and improved automatic telephone system wherein the setting impulses are delivered directly to the operating magnets of the automatic switches from the relays of the first trunk line or numerical switch of a train rather than from separate line relays individual to the several switches, respectively, of a train.

General description

15 As is well known, automatic telephone systems employing step-by-step switches fall into two general classifications, depending upon the method used for delivering the setting impulses to the magnets of the switches. The more common method is to employ a quick-acting line relay and a slow-acting release relay at each numerical switch, through the contacts of which impulses are delivered to position the associated switch. A number of so-called direct-pulsing systems have been developed, however, which employ the usual line relay and slow-acting release relay at the first switch of the train, but deliver impulses directly to the magnets of the subsequent switches in the train by way of one or both of the talking conductors extending through the connection established to the subsequent switches.

The present invention is concerned with improvements in systems of the second class, briefly outlined above, and it contains the following outstanding features:

1. In order to avoid the possibility of disturbances being set up in surrounding talking conductors responsive to the fairly heavy impulses of current delivered to the operating magnets of succeeding switches through the talking conductors, circuit arrangements are provided for operating the magnets of the switches succeeding the first-selector repeater over a loop circuit including the two talking conductors in series, and a series relay is provided in the switch being operated and is energized by the current flow in the talking conductor used as a return circuit for the operating magnet, thereby controlling the changeover from one movement to the next. In order to avoid the necessity of rendering the above-mentioned series relay slow-acting in the usual manual manner, together with the consequent necessity of a somewhat delicate adjustment, circuit arrangements are provided for

maintaining a sufficient current flow over the return conductor between impulses to maintain the series relay operated continuously throughout a series of impulses. By this arrangement, current impulses are transmitted over the two talking conductors in series to operate the operating magnet connected to one talking conductor, while between impulses the holding current is transmitted over the other talking conductor to maintain the series relay operated, whereby the changeover operation is separately controlled over the second talking conductor.

2. In order to realize the greatest possible economy without sacrificing reliability, the number of relays needed at the intermediate selectors and at the connectors have been reduced to a minimum by providing circuit arrangements whereby the functions of the relays eliminated are taken over by the remaining relays. In the connector, the ring-cut-off relay is used during the setting operation of the connector to control the changeover from the vertical movement to the rotary movement, and the busy relay is brought into play again when the calling subscriber replaces his receiver before the called subscriber does, and is operated over the called line to maintain the connector operated as long as the receiver is off the hook at the called substation, while the preceding switches in the train are released responsive to the receiver being replaced at the calling substation. In the intermediate selectors, the relays have been reduced to a series relay for changing over from the vertical movement to the rotary movement and a switching relay for connecting up the wipers at the end of the rotary movement, while the function of the release relay is taken over by the combined action of the two relays, which are both operated to close a circuit for the release magnet when the holding potential is removed from the release-trunk conductor.

3. An additional feature of the present arrangement is that no special circuit-altering arrangement need be made in the first selector repeater when an inter-office trunk line is taken for use, as circuit arrangements are provided for operating an impulse-receiving relay in the incoming selector in the called office over the first talking conductor in the same way that an operating magnet is operated over the first talking conductor in a local connection. The holding of the connection, together with the giving of supervision, is accomplished over the second talking conductor to which a high-resistance line relay is connected in the incoming selector repeater, be-

ing supplied with battery potential in order to hold up in series with the ground-connected lower winding of the back-bridge relay of the first selector repeater.

5 4. A special feature of the inter-office repeating arrangement is concerned with the provision of a ground connection to the second talking conductor in the selector repeater in order to enable the repeating relay in the distant incoming selector repeater to operate at the beginning of the first impulse, in combination with circuit arrangements in the incoming selector repeater for applying ground potential thereto in shunt of the ground connection to the lower talking conductor in the first selector repeater, thereby providing a loop circuit for the transmission of all impulses of a series following the beginning of the first impulse. It will be understood, of course, that a loop impulsive circuit is considered to be 10 more desirable in general than a ground-return impulse circuit because of the likelihood of differences in ground potential existing between two offices of a system.

25 Other objects and features of the invention, for the most part incidental to the objects and features hereinbefore enumerated and having to do mainly with the provision of suitable circuit arrangements for carrying out the required operations in a system such as outlined hereinbefore, 30 will become apparent upon a further perusal of the specification.

Description of drawings

35 Referring now to the accompanying drawings comprising Figs. 1-4, they show by means of the usual circuit diagrams a sufficient amount of apparatus in a telephone system embodying the features of the invention to enable the invention to be understood. In order for the drawings to 40 be understood best, Figs. 1-3 should be arranged in order, with Fig. 4 above Fig. 2. When the drawings are thus arranged, they show apparatus which may be involved in setting up a connection from the line of substation A1, Fig. 1, to the 45 line of substation A2, Fig. 3, in the same office and to the line of substation A3, Fig. 4, in a distant office.

50 Fig. 1 shows the office selector OS (a first selector repeater), which is accessible to line switches such as the line switch LS of substation A1.

55 Fig. 2 shows the thousands selector Th.S1 and the hundreds selector HS1 (intermediate selectors). The hundreds selector HS1 has two sets of wipers and is provided with a wiper-switching relay 253 to control the selection of wipers during the rotary movement, thereby giving access to twenty trunks on each level of bank contacts.

60 Fig. 3 shows the connector C1, which is accessible by way of one level of the hundreds selector HS1 and which has access to the line of substation A2.

65 Fig. 4 shows the thousands selector Th.S2 (an incoming selector repeater) in a distant office, together with the hundreds selector HS2 and the connector C2, which has access to the line of substation A3. The switches HS2 and C2 are indicated by dotted rectangles, but they may be similar to the switches HS1 and C1, respectively.

70 The numerical switches used in the present system are assumed to be two-motion switches of the regular Strowger type, while the line switch LS is assumed to be a rotary line switch of the usual construction and having the usual circuit arrangement. For this reason, the relays

associated with the line switch LS are not shown.

Detailed description

The invention having been described generally, 80 a detailed description of the operation of the apparatus shown will now be given. For this purpose it will be assumed that the subscriber at substation A1, Fig. 1, desires to converse with the subscriber at substation A2, Fig. 2.

Local call from substation A1 to substation A2

When the subscriber at substation A1 removes his receiver, the line switch LS operates in the usual manner over conductors 102 and 104 to extend conductors 102-104 by way of wipers 105-107 to an idle office selector or first selector repeater. Assuming that the office selector OS is the first one found to be idle, the connection is extended thereto by way of conductors 95 108-110.

Seizing the office selector OS

In the office selector OS, line relay 111 now operates over conductors 102 and 103 of the calling line and through contacts of relay 112. Upon operating, line relay 111 closes a circuit at its inner armature for release relay 114 in series with the resistance element 115; the inner armature of relay 111 being grounded by way of the 105 lower armature of relay 116 and off-normal spring 123. When relay 114 operates, it closes a locking circuit for itself at its inner lower armature; applies ground potential by way of the low-resistance lower winding of relay 112 to the windings of switching relay 118 at its inner upper armature; opens a point in the circuit of release magnet 120 at its upper armature; applies ground potential at its middle upper armature by way of contacts of relay 116 to release trunk conductor 109, thereby closing a holding circuit for the line switch LS; prepares an impulse-repeating circuit at its lower armature; and at its middle lower armature it closes a circuit by way of contacts of series relay 117, inner lower armature of relay 118, and the off-normal spring 127 and its lower contact for the meter-control relay 116. Relay 116 thereupon operates and prepares a locking circuit for itself at its inner lower armature; removes the normal ground connection from 125 the inner armature of line relay 111 at its lower armature and applies ground potential to the supervisory 1 conductor 133; and at its upper armature it shifts the connection between the middle upper armature of relay 114 and conductor 109 so that it includes the normally closed contacts controlled by the upper armature of back-bridge relay 113, preparatory to operating the marginally adjusted meter M when the call is answered.

Dial tone

The tone-start relay 137 is operated over the common tone-start conductor 135 in series with relay 116, thereby starting the various tone-generating devices of the exchange into operation. Current now flows from the dial-tone generator (not shown) by way of the common dial-tone conductor 136 to the lower conductor of the calling line by way of the middle lower armatures of 145 relays 118 and 117, lower armature of line relay 111, lower armature and resting contact of relay 117, the lower talking condenser, and contacts controlled by the lower armature of relay 112. Upon hearing the tone produced by the current- 150

flow from the dial-tone generator, the calling subscriber starts to dial the digits in the desired number.

5 *Setting the office selector OS*

When the first digit is dialled, the circuit of line relay 111 of the office selector OS is opened momentarily the desired number of times at the contacts of the calling device on the calling line.

- 10 Each time the circuit is opened, line relay 111 falls back momentarily. Each time line relay 111 falls back, it places a shunt around release relay 114 at the normally closed contacts controlled by its inner armature, thereby closing a circuit through the inner upper contacts of the meter control relay 116 for the series relay 117. Relay 117 operates responsive to the first shunt being placed around relay 114, and it remains operated throughout the series of impulses, owing 15 to the shunting effect of the resistance element 115 and owing to the current-flow through relays 117 and 114 in series, as well as because of the retarding effect of the copper collar provided on the heel end of the core of the relay, as indicated by the shaded lower portion. It will be understood, of course, that relay 114, being locked energized at its inner lower armature, does not fall back during the series of deenergizations of 20 relay 111 because of the local circulating current through its winding and through the contacts of line relay 111 while the relay is shunted.

- 25 As a further result of each deenergization of line relay 111, a connection is made between the upper and lower talking conductors on the wiper side of the talking condenser at the normally closed contacts controlled by the lower armature of line relay 111. This connection includes the lower armature of release relay 114. The vertical magnet 122 responds each time this connection is made between the two talking conductors, since it is connected to the wiper side of the upper talking conductor through the upper contacts of relays 118 and 112, while ground potential is supplied to the wiper side of the lower talking 30 conductor by way of the middle lower armature of relay 114, inner lower armature of the now-energized series relay 117, lower armature of relay 118, and the lower armature and resting contact of relay 112. For convenience in following the circuit of the vertical magnet 122, the complete circuit may be traced as follows:

- 35 From ground by way of the middle lower armature of relay 114, inner lower armature of the now-operated series relay 117, lower armature of relay 118, lower armature, normal, of relay 112, normally closed contacts controlled by the lower armature of relay 111, lower armature of relay 114, upper armature of relay 112, upper armature of relay 118, and vertical magnet 122 to the 40 battery.

- 45 By the operation of vertical magnet 122, the wipers 129-131 are raised step by step until they come to rest opposite the desired level of bank contacts. It is to be noted that the upper and lower windings of back bridge relay 113 are disconnected at the upper and lower armatures of the series relay 117 during the transmission of impulses to the vertical magnet, thereby preventing a premature operation of relay 113.

- 50 When the wipers 129-131 of the office selector OS are raised from their normal position, off-normal spring 127 opens the initial circuit of the meter-control relay 116, but off-normal spring 132 closes a locking circuit for relay 116 by way of the

lower contacts of back-bridge relay 113 and the inner lower armature of relay 116.

At the end of the series of impulses, relay 117 falls back, as the normal flow of current through its winding in series with the winding of relay 114 is insufficient to maintain it operated, for relay 117 is a low-wound, powerful relay and is moreover shunted by resistance element 115, whereas relay 114 is a relay of relatively high resistance and a large number of turns.

When relay 117 falls back, it completes a circuit at the normally closed contacts controlled by its lower armature for rotary magnet 139, which circuit includes the middle lower armature of relay 114, the inner lower armature of relay 118, and off-normal spring 127 and its upper contact, as well as the self-interrupting contacts of the rotary magnet. By the operation of the rotary magnet, the wipers 129-131 are driven step by step across the bank contacts in the selected level, in search of an idle trunk line. When an idle trunk line is reached, which trunk line, it will be assumed, is the one comprising conductors 134-156, wiper 130 encounters a battery potential on the test contacts of the idle trunk line, closing a circuit for the upper winding of switching relay 118. The left-hand terminal of the upper winding of switching relay 118 is supplied with ground potential by way of the low-resistance lower winding of the marginally adjusted switch-through relay 112 and the inner upper contacts of release relay 114. Battery potential is supplied to release trunk conductor 155 of the idle trunk line by way of overflow spring 209 and its left-hand contact, inner upper armature of relay 202, off-normal spring 204, resistance 217, and the supervisory relay 215.

When switching relay 118 operates, it opens the circuit of rotary magnet 139 at its inner lower armature so as to stop the rotary movement of the switch, at the same time closing a locking circuit for its lower winding in series with the rotary magnet 139; it opens a point in the dial-tone circuit at its middle lower armature; short circuits its upper winding so as to apply ground potential 115 more directly to the release-trunk conductor of the seized trunk line; and at its upper and lower armatures it disconnects the upper and lower talking conductors from the circuit of vertical magnet 122 and extends them by way of wipers 129 and 131 and conductors 154 and 156 to the thousands selector Th.S1.

Setting the thousands selector Th.S1

When the calling subscriber dials the second digit in the desired number, series relay 117 responds as before to the series of deenergizations of line relay 111. In addition, each deenergization of line relay 111 results in a bridge being placed across wipers 129 and 131 at the lower contacts of the relay and through contacts of relay 114. This bridge, it will be noted, includes the resting contacts of the upper and lower armatures of relay 112, and the corresponding armatures of the operated switching relay 118. Each time this bridge 140 is closed, vertical magnet 206 operates therethrough and over conductors 154 and 156 in series, ground potential being supplied to conductor 156 by way of the low-resistance lower winding of series relay 201 of the thousands selector Th.S1.

By the operation of vertical magnet 206, the wipers 211-213 of the thousands selector Th.S1 are raised step by step until they come to rest opposite the desired level of bank contacts. Relay 201 operates responsive to current flow in its lower 145 150

- winding when the first impulse of current is delivered to vertical magnet 206, and it remains operated throughout the series of impulses because of the shunting effect of the ground connection to the lower talking conductor at the office selector OS by way of the lower armature of series relay 117 and resistance element 126. Moreover, with relay 117 operated, a battery connection is made by way of the somewhat higher resistance element 125 through the lower armature of line relay 111 each time relay 111 reoperates at the end of an impulse. The current passing through resistance element 125 flows through the resistance element 126 and the lower winding of relay 201 in parallel. The current thus flowing over the lower talking conductor and through the lower winding of relay 201 between impulses is sufficient to maintain relay 201 operated throughout the series of impulses. It is to be noted that off-normal contacts 203, upon becoming closed when the wipers are raised from their normal position, close a circuit for the upper winding of series relay 201 and the lower winding of switching relay 202 in series, by way of the resistance element 210. No substantial current flows through the upper winding of relay 201 and the lower winding of relay 202 for the time being because, when off-normal spring 204 is allowed to shift from its normal position to open the circuit of supervisory relay 215, when the vertical movement starts, it permits the associated normally open off-normal contacts to close, thereby extending a ground potential from the release trunk conductor 155 to the junction of the lower winding of relay 202 and the resistance element 210, thereby shunting the current-flow away from the lower winding of relay 202 and the upper winding of relay 201. At the end of the series of impulses constituting the second digit, series relay 117 of the office selector OS falls back, removing the battery connection through the resistance element 125 from the lower talking conductor at its middle lower armature, at the same time shifting the lower talking conductor from in connection with resistance element 126 back to the lower winding of relay 113. When this occurs, the series relay 201 of the thousands selector Th.S1 falls back, thereby completing a circuit for rotary magnet 207 through the lower armature of switching relay 202 and off-normal contacts 208. Magnet 207 now operates in a buzzer-like manner to advance the wipers 211-213 over the bank contacts in the selected level in search of an idle trunk line. When an idle trunk line is reached, the trunk line comprising conductors 218-220, for example, the upper winding of switching relay 202 is energized responsive to wiper 212 encountering a battery potential on the test contact of the trunk line, supplied by way of conductor 219. Upon operating, relay 202 opens the rotary-magnet circuit at its lower armature, thereby terminating the rotary movement; closes a locking circuit for its lower winding in series with resistance element 210 at its inner lower armature; disconnects the incoming release-trunk conductor 155 from the junction of its lower winding and resistance element 210 in order to enable the locking circuit for the lower winding to become effective, at the same time short circuiting its upper winding so as to place a more effective guarding ground potential on the test wiper 212; and at its upper and lower armatures it disconnects the incoming talking conductors 154 and 156 from vertical magnet 206 and the lower winding of relay 201 and ex-

tends them by way of wipers 211 and 213 to the corresponding magnet and relay of the hundreds selector HS1.

It is to be noted that the ground potential supplied to the junction of the upper winding of relay 201 and the lower winding of relay 202 by the locking contacts of the latter relay prevents substantial current flow through relay 201, with the result that relay 201 remains in normal position.

In the hundreds selector HS1, the application of ground potential to release-trunk conductor 219 by way of wiper 212 results in current flow through the contacts controlled by overflow spring 221, inner upper armature of relay 252, off-normal spring 225, resistance element 259, the common supervisory conductor 263 and supervisory relay 264. Relay 264 thereupon becomes operated to indicate that a selector in the group containing the selector HS1 is in a seized and unoperated condition.

Setting the hundreds selector HS1

When the third digit is dialled, the current impulses are transmitted to vertical magnet 257 of the hundreds selector HS1 to bring about the elevation of the wipers 266-272 opposite the desired level of bank contacts, while series relay 251 is operated over the lower talking conductor in series with vertical magnet 257, and is maintained operated throughout the series of impulses, as explained in connection with series relay 201 of the thousands selector Th.S1.

When relay 251 falls back at the end of the series of impulses, it completes the circuit of rotary magnet 262, which has been prepared at off-normal contacts 261, whereupon rotary magnet 262 operates in a buzzer-like manner to drive the wipers across the bank contacts in the selected level.

When an idle trunk line is reached, relay 252 is operated through test wiper 267 or through test wiper 270 to seize the idle trunk. It is to be noted that the wiper switching relay 253 has its upper winding connected between test wiper 270 and the incoming release trunk conductor 219, by way of contacts controlled by the inner lower armature of relay 252. By this arrangement, wiper switching relay 253 is energized through wiper 270 as soon as the wipers 269-272 reach an idle trunk line, whether the trunk line then engaged by wipers 266-268 is idle or not. It will be understood, of course, that if the trunk line engaged by wipers 269-272 is in use, while the trunk line engaged by wipers 266-268 is idle, relay 253 is not operated, and relay 252 operates through wiper 267 to seize the trunk line accessible to the upper wiper set. Assuming that the wipers arrive upon the bank contacts terminating the trunk lines comprising conductors 281-283 and 284-286 at a time when the trunk line comprising conductors 284-286 is idle, relay 253 operates. Upon operating, relay 253 closes a locking circuit for itself at its lower contacts by way of off-normal contact 261; opens the rotary-magnet circuit at its middle lower armature; shifts the upper winding of relay 252 from test wiper 267 to test wiper 270 at its inner upper armature; and at its upper and lower armatures it shifts the talking conductor from wipers 266 and 268 to wipers 269 and 272.

At the same time, relay 252 operates sufficiently over wiper 267 to close its locking circuit, in case the upper trunk line is idle; but, if the upper trunk line is busy, relay 252 waits until

wiper 270 is connected up. Upon energizing, relay 252 opens an additional point in the circuit of rotary magnet 262 at its lower armature; closes a locking circuit for its lower winding at 5 its inner lower armature, at the same time disconnecting the left-hand terminal of the upper winding of relay 253, so as to prevent a subsequent energization of relay 253 in case this relay has not operated to switch wipers when relay 252 operates; shifts the incoming release-trunk conductor at its inner upper armature from in connection with the junction of its lower winding and resistance element 258 into connection with wiper 270 by way of inner upper armature of relay 253; and at its upper and lower armatures disconnects the incoming conductors 218 and 220 from magnet 257 and relay 251, and extends them by way of the upper and lower armatures of the operated relay 253 to conductors 20 284 and 286, by way of wipers 269 and 272.

Responsive to the application of ground potential to conductor 285 by way of wiper 270, current flows over conductor 285 and through the common supervisory relay 313, by way of 25 off-normal springs 307 and resistance element 306. Supervisory relay 316 thereupon operates for the usual purpose.

In the connector C1, release relay 301 is operated over conductor 285. Upon operating, relay 30 301 opens a point in the circuit of release magnet 312 at its lower armature; applies ground potential to locking conductor 331 at its inner upper armature; prepares a test circuit for the lower winding of relay 305 and a locking circuit for the upper winding of busy relay 301 at its upper armature; and at its inner lower armature it closes a circuit by way of off-normal spring 308 for the lower winding of relay 304. Relay 40 304 thereupon operates and prepares a locking circuit for itself at its inner lower armature, at the same time shifting the upper talking conductor, 284, from rotary magnet 309 to vertical magnet 310.

45 Setting the connector C1

When the calling subscriber dials the tens digit in the desired number, the consequent series of impulses is delivered over conductor 284 by way of armature 332 and its resting contact and the inner upper armature of relay 304 to vertical magnet 310. The circuit of vertical magnet 310 includes conductors 284 and 286 in series, conductor 286 being connected to the grounded holding conductor 331 in the connector by way of the 50 low resistance series relay 303 and contacts of relays 302 and 305. By the operation of magnet 310, the wipers 317-319 are raised step by step until they come to rest opposite the desired level of bank contacts. When off-normal spring 307 operates, upon the first vertical step of the switch, it shifts the circuit of the relay 316 from the incoming conductor 285 to the control of busy relay 302 at its inner upper armature.

Series relay 303 operates responsive to the first impulse of current delivered to magnet 310, and it remains operated throughout this series of impulses because of the inter-impulse current-flow permitted over the lower talking conductor by virtue of the above-mentioned connections made at the office selector OS to the lower talking conductor by way of resistance elements 125 and 126. When it operates, series relay 303 completes a locking circuit for the lower winding of ring-cut-off relay 304 at its inner lower armature, thereby maintaining relay 304 operated after its

initial circuit has been opened at off-normal spring 308.

When series relay 303 falls back at the termination of the train of impulses, it opens the locking circuit of relay 304 at its inner lower armature, whereupon relay 304 falls back and shifts the upper talking conductor from vertical magnet 310 to rotary magnet 309.

When the calling subscriber dials the final digit, the consequent impulses are delivered over conductor 284 to rotary magnet 309 by way of contacts of relays 305, 304, and 302. By the operation of the rotary magnet, the wipers 317-319 are rotated step by step over the bank contacts in the selected level until they come to rest upon the bank contacts connected to the called line. The series relay 303 is again operated throughout the series of impulses. At its inner upper armature, relay 303 disconnects test wiper 318 from the lower winding of switching relay 305 and connects it instead to the upper winding of busy relay 302; and at its upper and lower armatures it shunts the resting contacts of the upper and lower armatures of busy relay 302 so as to maintain the impulsing circuit intact in case busy relay 302 energizes during the rotary movement because of wiper 318 passing over busy test contacts.

The operation taking place at the end of the rotary movement depends upon whether the 105 called line is busy or idle, as will now be pointed out:

Called line busy

Assuming that the line of substation A2 is 110 busy when called, test wiper 318 encounters a ground potential on conductor 321 through the associated test contact, and busy relay 302 is energized through its upper winding and test wiper 318 when the wipers come to rest upon the desired set of bank contacts. With busy relay 302 energized, the falling back of series relay 303 results in a locking circuit being closed for the upper winding of busy relay 302 at the normally closed contacts controlled by the inner upper armature of relay 303. This locking circuit includes the middle upper armature of busy relay 302, armature 334, and the upper armature of release relay 301. With busy relay 302 operated, a connection exists between the busy tone conductor 314 and the lower talking conductor 286 at the lower armature of busy relay 302 and by way of the inner lower armature of switching relay 305. By virtue of this connection, a busy signal is transmitted back to the calling line. Upon hearing this busy tone, the calling subscriber is expected to replace his receiver and bring about the release of the operated switches in a manner similar to that to be hereinafter described.

It will be noted that magnet 309 and relay 303 135 are disconnected at the upper and lower armatures of relay 302.

Called line idle

Assuming that the line of substation A2 is idle 140 when called, no ground potential is encountered by test wiper 318 on conductor 321, with the result that busy relay 302 is in normal condition when the wipers 317-319 come to rest. Under this condition, the falling back of series relay 303 results in the closure of a test circuit for the lower winding of switching relay 305 through test wiper 318, which circuit is as follows: from ground by way of the upper armature of release relay 301, 150 armature 334, normal, middle upper armature,

normal, of relay 302, lower winding of relay 305, inner upper armature of relay 303, test wiper 318, and thence by way of the test contact on which wiper 318 is standing and conductor 321, to battery through the usual cut-off relay associated with the called line. Responsive to the current-flow through its lower winding, relay 305 operates and closes a locking circuit for its upper winding at its inner upper armature; prepares a locking circuit for the lower winding of ring-cut-off relay 304 at armature 335; at its inner lower armature it disconnects the lower talking conductor from series relay 303 and extends it to the disconnected lower winding of busy relay 302; disconnects the upper conductor from the rotary magnet at armature 332; connects up the wipers 317 and 319 at its upper and lower armatures; and at armature 334 it opens a point in the regular locking circuit of the upper winding of busy relay 302 and closes a circuit for the upper winding of busy relay 302 which includes the upper armature of relay 301. Busy relay 302 is thereby operated in preparation for the holding of the connector C1 under the control of the called line in case the calling subscriber is the first to replace his receiver.

The busy tone is not sent back to the calling line at this time because the busy-tone circuit includes the resting contact of the inner lower armature of the now-operated relay 305.

30 *Signalling the called subscriber*

With the wipers connected up at the upper and lower contacts of switching relay 305, ringing current now passes from the common generator lead 315 to the upper conductor 320 of the called line by way of the upper winding of ring-cut-off relay 304 and the upper armatures of relays 304 and 305. A return path to ground is provided for the ringing current by way of the lower talking conductor 322 and the lower armatures of relays 305 and 304.

40 *The called subscriber answers*

When the called subscriber responds to the ringing of his bell by removing his receiver, the ring-cut-off relay 304 is operated over its upper winding in the usual manner. Upon operating, relay 304 completes its locking circuit at its inner lower armature to conductor 331 by way of armature 335, and at its upper and lower armatures opens the ringing circuit and connects the wipers 317 and 319 to the incoming talking conductors 284 and 286.

In the office selector OS, back bridge relay 113, which is bridged across the wiper side of the talking condensers in series with the exchange battery, now operates in series with the telephone instrument at substation A2. Upon operating, back bridge relay 113 opens the locking circuit of the slow-acting meter-control relay 116 at its lower armature, and at its upper armature it connects the ungrounded terminal of a source of positive potential by way of resistance 119 to the incoming release trunk conductor 109, at the same time disconnecting release-trunk conductor 109 from ground potential at the upper armature of relay 114. After an interval, meter-control relay 116 falls back and at its upper armature it shifts the incoming release trunk conductor 109 back to ground potential again, at the same time opening an additional point in its locking circuit at its inner lower armature and disconnecting series relay 117 at its inner upper armature.

75 Responsive to the increased current flow caused by the momentary application of positive poten-

tial to conductor 109, the marginally adjusted meter M operates to register the answered call.

The two subscribers may now converse with each other as desired.

80 *Release of established connection; calling subscriber replaces receiver first*

It will now be assumed that the called subscriber is the first to replace his receiver when the conversation is terminated. Under this condition, when line relay 111 of the office selector OS falls back responsive to the receiver being replaced, it closes the usual bridge across the wiper side of the talking conductors at its lower contacts. Since back-bridge relay 113 is already in operated condition, the talking current is merely shunted away from the called line by this local bridge. At its inner contacts, line relay 111 places the usual shunt around release relay 114, but series relay 117 does not respond at this time, as it has been disconnected upon the falling back of the meter-control relay 116, above described.

After a slight interval, release relay 114 falls back responsive to the shunt being placed around its winding at the contacts of relay 111. Upon falling back, relay 114 opens its locking circuit at its inner lower armature; opens the local bridge across the talking conductors at its lower armature; removes ground potential from test wiper 130 at its inner upper armature, thereby bringing about the release of the switches of the train in a manner to be explained; removes ground potential from the incoming release-trunk conductor 109 at its middle upper armature, thereby permitting the line switch LS to release; opens the locking circuit of relay 118 at its middle lower armature; and at its upper armature it closes a circuit for release magnet 120 which includes contacts of relay 112 and off-normal contacts 121. Release magnet 120 operates to restore the office selector OS to normal position, whereupon the release-magnet circuit is opened at off-normal contacts 121.

Switching relay 118 having fallen back responsive to the opening of its locking circuit at the middle lower armature of release relay 114, the office selector OS is now in normal position, as back bridge relay 113 is deenergized responsive to the wipers being disconnected at the upper and lower armatures of relay 118.

As a result of the holding potential being removed from the release trunk conductor of the established connection at the inner upper armature of release relay 114 of the office selector OS, the upper windings of relays 201 and 251 are no longer short circuited, whereupon they are energized in series with the lower windings of relays 202 and 252, respectively. At the same time, sufficient current flows over the release trunk conductor of the established connection from ground by way of the windings of relays 201 and 251 to maintain release relay 301 of the connector C1 operated for the time being.

In the thousands selector Th.S1, the energization of relay 201 results in the closure of a circuit for release magnet 208 at the lower armature of the relay and through the lower armature of the operated relay 202, while in the hundreds selector HS1 the energization of relay 251 results in the closure of a similar circuit for release magnet 260. Release magnets 208 and 260 thereupon both operate, restoring the selectors Th.S1 and HS1 to normal position. When the selectors reach normal position, the relay circuits are opened at off-normal contacts 203 and 254, whereupon relays

201, 202, 251, and 252 fall back, opening the circuits of release magnets 208 and 260.

In the connector C1, release relay 301 falls back responsive to wiper 270 leaving the contact on 5 which it has been standing. When relay 301 falls back, it closes a point in the circuit of release magnet 312 at its lower armature, but release magnet 312 is controlled also at the inner lower armature of busy relay 302, which is now operated; and at its upper armature it opens the initial circuit of the upper winding of busy relay 302. Busy relay 302, however, does not fall back at this time, but remains operated over the called line (it having been assumed hereinbefore that 10 the receiver is still off the hook in the called substation), because a holding circuit is closed to the called line for the upper and lower windings of busy relay 302 in series at the upper contacts of relay 301 and at the contacts controlled by the 15 inner lower armature of the relay. The lower winding of relay 302 is now connected between ground and the lower talking conductor by way of the inner upper armature of relay 302, armature 335, inner lower armature of ring-cut-off relay 304, and the contacts controlled by the inner 20 lower armature of relay 301. At the same time, the upper winding of relay 302 is connected between the ungrounded pole of the exchange battery and the upper talking conductor by way of the operated armature 334 of relay 305 and the 25 contacts controlled by the upper armature of relay 301. As long as busy relay 302 remains operated over the called line, it maintains ground potential on conductor 331, thereby maintaining 30 relays 304 and 305 operated. By maintaining a guarding ground potential on conductor 331 at armature 333, relay 305 maintains the called line guarded, and it thereby prevents a false operation 35 of the line switch (not shown) individual to the called line. Also, the connector C1 is in a guarded condition, since the battery potential applied to conductor 285 through relay 301 is insufficient to mark the incoming trunk line idle, because of the relatively high resistance of the 40 relay winding.

The called subscriber replaces his receiver

When the called subscriber replaces his receiver, busy relay 302 falls back and removes ground potential from conductor 331 at its inner upper armature, permitting relays 304 and 305 to fall back. At its inner lower armature, relay 302 closes a circuit for release magnet 312, whereupon release magnet 312 restores the connector C1 to 55 normal position. The circuit of release magnet 312 is thereupon opened at off-normal spring 308.

The entire connection is now released and all the apparatus involved therein is in readiness to be used in setting up subsequent connections.

Release of the established connection when the called subscriber hangs up first

Assuming now that the subscriber at substation A2 is the first to replace his receiver when the 60 conversation is terminated over the hereinbefore described connection, back bridge relay 113 of the office selector OS falls back when the receiver is replaced, but produces no particular result other than the placing of a ground potential at its lower armature on the supervisory 1 conductor 134, for a purpose to be described hereinafter. Under this condition, when the subscriber at substation A1 replaces his receiver, the release of the selectors OS, Th.S1, and HS1 takes place as described. In 65 the connector C1, the deenergization of relays 302,

304, and 305, and in the immediate operation of release magnet 312, as busy relay 302 is not maintained operated over the called line.

Inter-office call from the subscriber at substation A1 to the subscriber at substation A3

It will now be assumed that the subscriber at substation A1, Fig. 1, desires to converse with the subscriber at substation A3, whose line terminates in a distant office of the system. Assuming that the line switch LS extends the calling line to the office selector OS when the receiver is removed, the office selector OS is prepared for operation in the hereinbefore-described manner and dial-tone current is transmitted back to the calling substation.

Setting the office selector OS

When the first digit in the desired number is dialled, the office selector OS responds under the control of vertical magnet 122 as hereinbefore described by raising its wipers 129-131 opposite the desired level of bank contacts. At the end of the setting operation, the trunk-hunting operation ensues, during which wipers 129-131 are driven step by step over the selected level of contacts in search of an inter-office trunk line extending to the desired distant office. Assuming that the trunk line comprising conductors 151-153 is the first one found to be idle, this trunk line is taken for use, as the trunk-hunting operation is stopped responsive to the operation of switching relay 118 through wiper 130 and by way of the resistance element associated with conductor 152.

As soon as the inter-office trunk line is seized, line relay 402 in the thousands selector Th.S2, Fig. 4, operates over conductor 153 in series with the lower winding of back-bridge relay 113 of the office selector OS, Fig. 1. Back-bridge relay 113 is not operated at this time owing to the high resistance of the upper winding of line relay 402. The two windings of line relay 402 are connected between the ungrounded pole of the exchange battery and conductor 153 by way of the upper contacts of relay 403 and the lower left-hand repeating-coil winding. Line relay 402 closes a circuit through the off-normal contacts 407 for release relay 401, whereupon release relay 401 operates and prepares circuits at its middle upper and upper armatures for the windings of switching relay 406; closes a locking circuit for itself at its inner upper armature independent of off-normal contacts 407; and at its lower armature opens a point in the circuit of release magnet 411 and prepares a circuit for rotary magnet 415.

Setting the thousands selector Th.S2

When the calling subscriber dials the thousands digit in the desired number, the impulses generated at the lower contacts of line relay 111 of the office selector OS are delivered over the upper talking conductor and by way of the inter-office trunk conductor 151 to the impulse relay 405 of the thousands selector Th.S2, through the upper left-hand repeating-coil winding and the inner armature of back-bridge relay 403. The return path for the beginning of the first impulse-series relay 107 of the office selector OS operates as before explained—is to ground at the office selector OS through resistance element 128. A series circuit over conductors 151 and 153 is established, however, for the final portion of the first impulse and for the remaining impulses of the series, as will be pointed out hereinafter.

In the thousands selector Th.S2, each time impulse relay 405 responds to an impulse, it closes a circuit for vertical magnet 409 at its upper armature, which circuit includes the upper and lower armatures of switching relay 406. By the operation of vertical magnet 409, the wipers 418—420 are raised step by step until they come to rest opposite the desired level of bank contacts. The slow-acting series relay 404 is operated at 10 the inner lower contacts of relay 405 upon the first impulse, and it remains operated throughout the series. At its inner lower armature, relay 404 places ground potential on the upper terminal of the lower left-hand repeating-coil winding, by way of the lower armature of release relay 401, thereby extending a ground potential back over conductor 153 to the originating exchange so as to form a loop circuit over conductors 151 and 153 for the delivery of the remaining 15 impulses. This new ground connection is in shunt of the ground connection to the lower talking conductor at the office selector OS by way of resistance element 126.

At the end of the series of impulses, series relays 117 and 404 of the switches OS and Th.S2, respectively, fall back. When relay 404 falls back, it completes a circuit for rotary magnet 416 at its inner lower armature through the inner lower armature of relay 406 and the off-normal spring 415. Rotary magnet 416 thereupon operates in a buzzer-like manner to advance the wipers 418—420 over the bank contacts in the selected level in search of an idle trunk line.

When an idle trunk line is reached, which 35 trunk line it may be assumed is the one extending to the hundreds selector HS2, the upper winding of switching relay 406 becomes energized through wiper 419, operating the relay to open the circuit of rotary magnet 416 and close a locking 40 circuit for the lower winding through the rotary magnet. At its inner upper armature, relay 406 supplies ground potential directly to wiper 419, and at its upper and lower armatures it disconnects the talking conductors from magnet 409 45 and from ground and extends them by way of wipers 418 and 420 to the hundreds selector HS2.

Setting the hundreds selector HS2

When the hundreds digit is dialled, the consequent 50 impulses are repeated by the office selector OS to the impulse relay 405 of the thousands selector Th.S2, whereat the impulses are repeated at the upper contacts of relay 405 to the hundreds selector HS2.

The hundreds selector HS2, which may be the 55 same as the selector Th.S1, Fig. 2, responds to the received impulses by raising its wipers opposite the desired level of bank contacts and in rotating them over the selected level of bank contacts in search of an idle trunk line. It will be assumed that the trunk line extending to the connector C2 is the first one found to be idle, in which case this trunk line is seized and the connector C2 is prepared for operation as explained in connection with the connector C1, Fig. 3.

Setting the connector C2

When the final two digits of the number are 70 dialled, the impulses are delivered to the connector C2, which responds by raising its wipers opposite the desired level of bank contacts and in then rotating its wipers over the contacts in the level until they come to rest upon the bank

contact connected with the line of substation A3. If the line is busy, a busy-tone current is transmitted back to the calling line as explained in connection with the connector C1, but if the called line is idle, the connection is made and ringing current is applied to signal the called subscriber.

The called subscriber responds

When the called subscriber responds to the 85 ringing of his bell by removing his receiver, the ring-cut-off relay (not shown) in the connector C2 operates in the usual manner to complete the talking connection, whereupon back bridge relay 403 is operated over the called line. Upon operating, back bridge relay 403 disconnects the battery potential from the upper terminal of the upper winding of line relay 402 and it places the low-resistance lower winding of line relay 402 in shunt of the talking condenser associated with the left-hand repeating-coil windings, at the 90 same time disconnecting impulse relay 405. When this occurs, line relay 402 remains energized over conductors 151 and 153 in series, and back-bridge relay 113 in the office selector OS energizes in 95 series with the lower winding of line relay 402 in the distant office, with results described hereinbefore.

Releasing the established connection

It will be assumed that the subscriber at substation A3 is the first to replace his receiver after the conversation is terminated. When this is done, back-bridge relay 403 of the thousands selector Th.S2 falls back, disconnecting the lower winding of relay 402 from in bridge of conductors 151 and 153 and again connecting the upper terminal of the upper winding of line relay 402 to battery to re-establish the initial holding circuit of the line relay. When this occurs, back-bridge relay 113 of the office selector OS falls back because of the high resistance of the upper winding of line relay 402.

When the subscriber at substation A1 replaces 110 his receiver, line relay 112 falls back and places a bridge across the wiper side of the talking conductors, re-operating back-bridge relay 113. At the same time, release relay 114 is shunted at the inner contacts of relay 111, causing release relay 114 to fall back and bring about the release of 115 the office selector OS as hereinbefore described.

In the thousands selector Th.S2, line relay 402 falls back and opens the circuit of release relay 401. After a slight interval, release relay 401 of the thousands selector Th.S2 falls back and 120 removes ground potential from wiper 419 at its upper armature; opens the locking circuit of switching relay 406 at its middle upper armature; opens a further point in its own circuit at its inner upper armature; and at its lower armature 125 it closes a circuit for release magnet 411 through off-normal springs 410. By the operation of release magnet 411, the thousands selector Th.S2 is restored to its normal position in the usual manner, whereupon the release magnet circuit is opened at off-normal springs 410. It is to be noted that relay 401 cannot become re-operated, even though the trunk line is again seized in the other office immediately, until the switch is restored to its normal position and a circuit is prepared for relay 401 at off-normal contacts 407.

The selector HS2 and the connector C2 are released in the manner explained in connection with the switches of Figs. 2 and 3.

Supervising the office selector OS

In order to supervise the office selectors, two supervisory signals (not shown) are provided, controlled over conductors 133 and 134, respectively, which conductors are common to a plurality of selectors. It will be recalled that the meter-control relay 116 is operated at the middle lower armature of release relay 114 when the office selector OS is taken for use. When it operates, relay 116 closes a circuit at its lower armature by way of off-normal contacts 123 and over the common conductor 133 for the first supervisory signal. This circuit is opened as soon as the office selector OS is moved from its normal position. By observing this signal, an attendant can determine whether or not there is an office selector in a seized and unoperated condition.

It will be recalled also that the meter-control relay 116 is deenergized following the operation of back-bridge relay 113 when the call is answered. With relay 116 in normal position, the falling back of back-bridge relay 113 responsive to the called subscriber replacing his receiver before the calling subscriber does so results in the closing of a circuit over the second supervisory conductor 134 at the lower contacts of back-bridge relay 113. This circuit includes off-normal spring 123 and its upper contact, and the inner lower armature of relay 116. This circuit is opened as soon as the calling subscriber replaces his receiver and brings about the restoration of the office selector OS to normal.

Supervising the intermediate selectors

It is to be noted that a supervisory relay 215 is provided common to a plurality of the thousands selectors such as the thousands selector Th.S1. This supervisory relay is operated in series with any resistance element such as resistance element 217 when one of the associated thousands selectors is taken for use. The circuit of relay 213 is opened at off-normal spring 204 when the thousands selector Th.S1 is operated. In a similar way, supervisory relay 264 controls the signal common to the hundreds selectors such as the hundreds selector HS1, being controlled over the common conductor 263 through resistance elements such as the resistance element 259 of the hundreds selector HS1.

Supervising the connector C1

The connector C1 is supervised in a manner similar to the intermediate selectors of Fig. 2, there being a common supervisory relay 316 controlled over the common supervisory conductor 313 through resistance elements such as the resistance element 306 individual to the connector C1. The supervisory circuit is opened, it will be noted, by busy relay 302 when this relay operates responsive to a busy condition or responsive to the closing of a local circuit for it when switching relay 305 operates responsive to an idle condition of the called line. By this arrangement, the supervisory circuit is closed first over the incoming conductor 285 when the switch is taken for use, and is then placed under the control of busy relay 302 as soon as off-normal springs 307 operate, and it remains closed until connection is completed to an idle line or until the called line is found to be busy. In this way, the supervisory signal controlled by relay 316 indicates whether or not there are any connectors in a seized position which have not been completely operated.

Supervising the incoming thousands selector Th.S2

When the release relay 401 of the thousands selector Th.S2, Fig. 4, operates responsive to the associated trunk line being taken for use, it closes a circuit at its lower armature by way of the lower armatures of relays 404 and 406 and through off-normal spring 415 and resistance element 417 over the associated supervisory lead to bring about an operation of the connected supervisory signal. This circuit is opened at off-normal spring 415 as soon as the switch moves from its normal position.

Overflow at the office selector OS

In case the office selector OS is unable to find an idle trunk line in a selected level, the rotary movement continues until the wipers 129-131 have been driven beyond the last set of bank contacts, whereupon the overflow contacts 124 and 128 are closed by the usual cam arrangement carried by the shaft of the switch. When cam springs 128 close, the lower winding of relay 118 is operated in series with vertical magnet 122, thereby operating relay 118 to disconnect the vertical magnet circuit from the talking conductor and to open the dial-tone circuit. Overflow springs 124 close a circuit path for transmitting busy-tone current by way of conductor 132 to the upper conductor of the called line. Upon hearing the busy tone, the calling subscriber is expected to replace his receiver and bring about the release of the office selector OS in the usual manner.

Overflow at the intermediate selectors

When the thousands selector Th.S1 is unable to find an idle trunk in the selected level, and the overflow springs 209 and 205 are operated, overflow spring 209 removes the shunt from around the lower winding of relay 202 and connects the incoming release trunk conductor 155 to the junction of the windings of relays 201 and 202 so as to maintain the upper winding of relay 201 shunted. When this operation occurs, relay 202 operates to open the rotary magnet circuit and thereby stop the rotary movement. With overflow contacts 205 closed, a busy-tone circuit is completed to the upper talking conductor 154 as soon as relay 202 operates, thereby transmitting a busy tone back to the calling line to prompt the calling subscriber to replace his receiver and bring about the release of the connection.

An overflow condition at the hundreds selector HS1 results in an operation of relay 252 under the control of overflow spring 221, which places a new shunt around the upper winding of relay 251 and removes the shunt from around the lower winding of relay 252. When relay 252 operates to terminate the rotary movement, it completes the busy-tone connection to conductor 218 at its upper armature by way of overflow springs 256.

Overflow at the incoming selector repeater Th.S2

When an overflow condition is encountered at the incoming thousands selector repeater Th.S2, Fig. 4, the closure of overflow contacts 414 results in the energization of switching relay 406 in series with vertical magnet 409 to open the rotary magnet circuit. The busy-tone current is transmitted back as the result of a connection between the common busy-tone conductor and the lower talking conductor by way of overflow contacts 413.

Tandem connections

It is to be noted that the incoming thousands selector Th.S2, by being equipped with resistance elements 408 and 412, is arranged in a manner 5 similar to the office selector OS, as regards the repeating of impulses. By this arrangement, a call may be extended from the first office to the incoming thousands selector Th.S2 in the distant office and thence by way of the incoming thousands selector to a third office, if the trunking system is so arranged. The third office, of course, 10 may be a sub-office of the second office. In any case, impulses are repeated from the second office to the third office in substantially the same manner 15 that they are repeated from the first office to the second office. It is to be noted, however, that the first impulse of a series repeated by the thousands selector Th.S2, either to an intermediate selector in the same office or to an incoming 20 selector in a third office, is the same as any subsequent impulse in the series, as the impulse relay 405 is so connected in the impulsive circuit that the first impulse does not await the operation of the series relay 404, as in the case of the office 25 selector OS, Fig. 1, wherein the number of contacts controlled by line relay 111 must be kept to a minimum, and the first impulse awaits the operation of series relay 117.

30 *Switching through at the office selector OS*

It is customary in telephone systems of the character disclosed herein to arrange the office selector, or first selector repeater, so that the talking conductors may be extended metallically 35 therethrough and independent of bridges, when the destination of the call makes this desirable, such as, for example, when extending a connection to a so-called ring-back switch in a party-line call, and the like.

40 Trunk circuits which require that the office selector be switched through are especially arranged so that a connection is momentarily made therein to the ungrounded pole of the exchange battery by way of a relatively low resistance, thereby 45 bringing about a greatly increased flow of current over the release trunk conductor of the established connection and through test wiper 130 of the office selector OS. This current flow passes 50 through the low-resistance lower winding of the marginally adjusted switch-through relay 112, causing relay 112 to operate. Upon operating, relay 112 locks itself to the grounded conductor 55 109 at its inner upper armature; extends the grounded conductor 109 through to the test wiper 60 at armature 161; opens an additional point in the circuit of the release magnet at armature 162; closes a new holding circuit for the lower winding 65 of switching relay 118 at its inner lower armature; and at its upper and lower armatures it extends the incoming conductors 108 and 110 to the wipers 129 independent of the talking condensers and 70 cuts off the front and back bridges, thereby giving an unbridged metallic connection through the 75 selector.

As a result of the front-bridge line relay 111 being disconnected, this relay falls back and shunts release relay 114, causing relay 114 to fall back also. No harm results from the de- 70 energization of relay 114 at this time, as the essential work of this relay in maintaining the connection has been taken over by relay 112 as above pointed out. The trunk circuit to which the 75 connection is now extended must be arranged, however, to apply ground potential to the re-

lease-trunk conductor immediately after the above-mentioned heavy application of battery potential, thereby maintaining the release-trunk conductor grounded to maintain the connection intact until the receiver is replaced.

What is claimed is:

1. In an automatic telephone system, an automatic switch having a pair of talking conductors incoming thereto, a separate return conductor, an operating magnet for said switch connected between one talking conductor and said return conductor, a control relay for said automatic switch connected between the other incoming talking conductor and said return conductor, means for transmitting current impulses over the said two incoming talking conductors in series to operate said magnet to position the switch and to operate the controlling relay to control the positioning operation.

2. In an automatic telephone system, an automatic switch having a pair of talking conductors incoming thereto, a separate return conductor, an operating magnet for said switch connected between one talking conductor and said return conductor, a control relay for said automatic switch connected between the other incoming talking conductor and said return conductor, means for transmitting current impulses over the said two incoming talking conductors in series to operate said magnet to position the switch and to operate the controlling relay to control the positioning operation, and means effective while a series of impulses is being transmitted for maintaining a reduced current flow through said control relay and over the associated talking conductor during the inter-impulse intervals, whereby said control relay is maintained operated continuously throughout a series of impulses.

3. In a telephone system, an impulse repeater and an automatic switch inter-connected by a pair of talking conductors, a battery-feed relay bridged across said talking conductors at the impulse repeater, an operating magnet bridged across said talking conductors at the automatic switch, and means at the repeater for transmitting a series of impulses over said talking conductors to said automatic switch to actuate said operating magnet and for maintaining said battery-feed relay disconnected from in bridge of said talking conductors during the transmission of impulses.

4. In combination, an impulse repeater and an automatic switch inter-connected by a trunk line including a pair of talking conductors, a bridge across said conductors at the repeater for supplying transmitter-energizing current, a bridge across the talking conductors at said automatic switch including an operating magnet, means at the impulse repeater for transmitting a series of impulses over said talking conductors to actuate said operating magnet, and means at the impulse repeater actuated throughout the transmission of impulses for disconnecting said current-supply bridge.

5. In a telephone system, an automatic switch having an operating magnet, a talking conductor extending to said operating magnet, a battery-feed relay having a winding connected between the exchange battery and said talking conductor, means for transmitting a series of impulses over said talking conductor to actuate said operating magnet, and means for opening the connection through said relay winding for the duration of the transmission of impulses to prevent a premature actuation of said relay.

6. In an automatic telephone system, means including a train of automatic switches for setting up a connection to a called line, an automatic repeater preceding said train of switches, a 5 battery-feed relay in said repeater connected in bridge of the talking conductors thereat to supply transmitter current to the called line through the connection when it is established, means in said repeater for transmitting series of impulses over one talking conductor to actuate the automatic switches to set up the connection, and means in said repeater actuated for the duration of each series of impulses to disconnect said battery-feed relay from the talking conductor 10 over which the impulses are transmitted. 80
7. In a telephone system, a connector switch having access to subscribers' lines, means for operating said switch into association with any line and for completing connection thereto in 15 case the line is idle, a busy relay in said connector actuated responsive to the line being in a busy condition to prevent connection being made therewith and to send back a busy signal to the calling line, means for operating said busy relay 20 as a holding relay when connection is completed to a called line, and means for maintaining said busy relay operated over the called line to maintain said connector switch operated after the calling subscriber replaces his receiver in case the 25 called subscriber is the last to replace his receiver. 85
8. In a telephone system, an intermediate selector having a series relay and a switching relay, means for operating said selector to bring it into association with a desired group of trunk lines and for operating said series relay and for maintaining it operated until the desired group of 30 trunk lines has been reached, means controlled by said series relay and effective when it restores 35 for causing said selector to search for an idle trunk line in the selected group, a switching relay and means for operating it to seize an idle trunk when one is found, a release magnet for 40 restoring said selector to its normal position, means for operating both of said relays to restore 45 the selector, and an operating circuit for said release magnet including contacts of both relays in series and closed only when both relays are actuated. 100
9. In an automatic switch, a first relay and 50 means for operating it momentarily while the switch is being positioned, a second relay and means for operating it after the switch has been positioned, means effective when the switch is to be restored to normal position for maintaining 55 the second relay operated and for re-operating the first relay, and means responsive to both relays being operated at the same time for restoring said switch to its normal position. 105
10. In a telephone system, an automatic switch 60 having two sets of wipers, two groups of trunk lines accessible to said wiper sets respectively, one set of said wipers being normally connected up to the switch for use, while the other set of wipers is normally disconnected, and means effective whenever the trunk line engaged by the 65 normally disconnected set is idle for substituting the normally disconnected set of wipers for the normally connected set. 110
11. In an automatic telephone system, an automatic switch having two sets of wipers, trunk lines arranged to be tested over by said wiper sets, two test relays associated with said wiper sets respectively, means for advancing said wipers until an idle trunk line is found by either or both 70 sets, means for operating the first test relay 115
- through a wiper in the first set in case the trunk line encountered thereby is idle, whereby a connection is made to the trunk line engaged by the first set of wipers by way of normally open contacts of the first test relay and normally closed contacts of the second test relay, and means for operating the second test relay over a wiper in the second set in case the trunk line encountered thereby is idle and whether the trunk line encountered by the first set is busy or idle to seize the trunk line encountered by the second wiper set through normally open contacts of both test relays, and means responsive to the operation of either test relay for stopping the advance of the wipers. 80
12. In a telephone system, a trunk line comprising a pair of talking conductors and extending to an automatic switch, an impulse relay in said automatic switch controlled over the first of said talking conductors, a holding relay in said automatic switch controlled over the second talking conductor, means for taking said trunk line for use and for setting up a current flow over the second talking conductor to operate said holding relay and to maintain it operated for the purpose of 85 holding said automatic switch after it has been operated, means for transmitting a series of impulses over the first talking conductor to operate said impulse relay to bring about the setting of said automatic switch, a resistance element, circuit arrangements for transmitting the first impulse of current over said first talking conductor and through said resistance element in a circuit path independent of the second talking conductor, and means in said automatic switch responsive to said first impulse of current for placing the second talking conductor in shunt of said resistance element, whereby the remaining impulses are transmitted over the two talking conductors in series to said impulse relay. 90
13. In a telephone system, a two-conductor trunk line extending to an automatic switch, an impulse relay in said automatic switch connected to the first of said conductors and arranged to repeat impulses from the conductors to the automatic switch, means for transmitting a series of impulses over said conductors to said impulse relay to bring about an operation of said switch, a resistance element, circuit connections for transmitting the first impulse over the first conductor 100 through said resistance element and independent of the second conductor, and means responsive to the transmission of the first impulse for placing the second conductor in shunt of said resistance element to enable the subsequent impulses to be 105 transmitted over the two conductors in series. 110
14. In a telephone system, a two-conductor trunk line extending to an automatic switch, a holding relay in said automatic switch connected to the second of the trunk-line conductors, means for delivering operating impulses to said automatic switch over the first of said trunk-line conductors, means for maintaining the holding relay operated over the other of said conductors to maintain the switch in its operated position, and 115 means effective in said automatic switch while the setting impulses are being received for closing a local holding circuit for said holding relay independent of the second conductor. 120
15. In an automatic multi-exchange telephone system, a trunk line extending from a first office to a second office, means for transmitting a series of setting impulses from the first office to the second office over one conductor of said trunk line, 125 means in the first office for making an applica- 130
16. In an automatic telephone system, a trunk line 135

tion of ground potential to the second talking conductor to enable the first impulse of a series to be delivered to the second office over the first talking conductor and through a bridge across the 5 talking conductors and said ground connection, and means in the second office responsive to the first impulse for making a ground connection to the second talking conductor in the second office in shunt of the first-named ground connection 10 in order to enable the subsequent impulses to be delivered to the second office over the two conductors in series.

16. In an automatic telephone system, a selector switch, a trunk line incoming thereto including 15 a pair of talking conductors, an operating magnet for said switch, a control relay for said switch, a circuit for said magnet and relay including the two talking conductors in series, and an auxiliary holding circuit for said control relay 20 including only one of said talking conductors and ground.

17. In an automatic telephone system, an impulse repeater and an automatic switch interconnected by a pair of talking conductors, an operating magnet and a change-over control relay bridged across the talking conductors at said 25 switch in series with the battery, a line relay at the repeater, a bridge closed across the talking conductors by said line relay each time it deenergizes in repeating a series of impulses, said bridge completing a circuit for operating said magnet and changeover relay in series, and means controlled by the line relay each time it energizes in 30 repeating a series of impulses for closing an auxiliary circuit over only one talking conductor to maintain said changeover relay energized.

18. A selector switch having a directive primary

movement and an automatic secondary movement, said selector having only two relays, means for energizing the first relay during the primary movement and for deenergizing it at the end thereof to start the secondary movement, means for energizing the second relay to stop the secondary movement, and means for energizing both relays to release the switch.

19. A two motion selector switch having a combined changeover and release relay, means for energizing said relay during the primary movement and for deenergizing it at the end thereof to start the secondary movement, a circuit closed on completion of the secondary movement for again energizing said relay to release the switch, a release conductor, and connection from said conductor to said relay circuit whereby a holding potential on said conductor prevents said relay from energizing.

20. In a selector switch, a wiper connecting relay, a test conductor on which a potential is maintained to hold said relay energized, a release circuit prepared by said relay, and a second relay which is shunted by said potential and which energizes in series with said first relay when the potential is removed to complete said release circuit.

21. In a selector switch, a test conductor on which a potential may be maintained to control the release of the switch, a relay, means for closing a circuit for said relay when the switch is operated, a connection to said circuit from said conductor whereby the potential thereon prevents the relay from energizing, and a release circuit controlled by said relay when it energizes responsive to the removal of said potential.
